COMBINED FACE AND HANDS FOR A CLOCK

Roy Lee Baker, Rural Route, Shipman, Ill. 62685

Filed June 14, 1967, Ser. No. 7,474

Term of patent 14 years

(Cl. D42—7)

FIG. 2

FIG. 1 is a front elevational view of a combined face and hands for a clock showing my new design, and

FIG. 2 is a cross-sectional view taken on line 2—2 of FIG. 1.

The coins shown schematically in broken lines are for illustrative purposes only.

I claim:

The ornamental design for a combined face and hands for a clock, substantially as shown and described.
